UNITED STATES PATENT OFFICE.

JOHN P. DORAU, OF JEFFERSON, WISCONSIN.

CLOTHES-POUNDER.

1,172,680.

Specification of Letters Patent. Patented Feb. 22, 1916.

Application filed March 27, 1914. Serial No. 827,649.

To all whom it may concern:

Be it known that I, JOHN P. DORAU, a citizen of the United States, residing at Jefferson, in the county of Jefferson and 5 State of Wisconsin, have invented a new and useful Clothes-Pounder; and I do hereby declare the following to be a full, clear, and exact description of the invention, such as will enable others skilled in the art to 10 which it appertains to make and use the same.

This invention relates to clothes pounders and the like. It is a device to facilitate the washing of clothes in the tub, being capable 15 of performing the maximum amount of work with the minimum expenditure of energy. While designed to give the greatest strength in the simplest mechanical structure, it can be easily and cheaply made and 20 will, therefore, more universally commend itself. The pattern herewith illustrated is thought to embody the most efficient design. Nevertheless, the inventor reserves the right to make any changes or alterations that are 25 not foreign to his appended claim.

In the drawings:—Figure 1 is a plan view of the improved clothes pounder. Fig. 2 is a section on the line 2—2 of Fig. 1. Fig. 3 is a sectional view on line 3—3 of Fig. 2. 30 Fig. 4 is a sectional view on line 4—4 of Fig. 2.

The device consists essentially of the air chamber 1 having the side walls 2 and the top plate 3. The cylindrical rib 4 runs 35 around the entire lower edge of the walls 2 and besides giving added strength to the chamber 1 forms a rounded edge that will not tear or mar the clothes.

The air chamber is so shaped that it has 40 its greatest width and therefore its greatest volume at points remote from the center and when it is remembered that the greater bulk of clothes is away from the center of the tub, the advantage of this increased volume is readily apparent.

In Fig. 1 the relative proportions of the pounder and tub are shown, the tub being designated by the letter T.

A casting 5 serves as a support for the 50 air chamber to which it is secured by the screws 6. This casting also carries the operating handle 7, the pin 8 serving to hold said handle in position.

Copies of this patent may be obtained for five cents each, by addressing the "Commissioner of Patents, Washington, D. C."

A check valve is included in the design of the casting 5, the air inlet 9 leading to the 55 ball valve 10 and the air outlet 11 into the air chamber 1.

The pounder is operated by imparting to it a reciprocating motion and at the same time an intermittent rotary motion and this 60 may be done either by machinery or by hand. If a machine is used, any conventional forms of combining a constant reciprocating motion with an intermittent rotary motion may be employed.

When the pounder is pressed down upon the clothes, the air in chamber 1 is compressed and seeking an outlet through the duct 11 presses the ball 10 upon its seat. Being thus prevented from escape through 65 the valve 10 it is forced through the clothes, carrying away the dirt. On the upward stroke the air in 1 is rarefied, the pressure on valve 10 is released and equilibrium is restored by the inrush of air through the 70 inlet 9. The repetition of these movements followed by the condensation and rarefaction of the air very quickly rids the clothes of all dirt without the harmful effects which 75 invariably follow scrubbing.

The invention having been set forth, what 80 is claimed as new and useful is:—

A valve structure for a reciprocating casting, comprising a casting extending through the upper wall of the casing and depending 85 below the wall, a duct formed in the casting and passing from the upper surface thereof downward in the casting to a substantially elbow turn and provided with a valve seat adjacent to the termination of the elbow 90 turn, said duct then extending upwardly substantially parallel with its downwardly valve seat being larger in diameter than the right-angled outlet opening, said upwardly extending portion immediately above the 95 extending portion and terminating in a valve seat and the first part of the duct, and a ball valve coöperating with the seat.

In testimony whereof I have signed my name to this specification in the presence of 100 two subscribing witnesses.

JOHN P. DORAU.
